Fredrick H. Griffith,

By Bernard F. Lane
Attorney

UNITED STATES PATENT OFFICE.

FREDRICK H. GRIFFITH, OF JOHNSTOWN, PENNSYLVANIA.

HAIR CRIMPER AND CURLER.

Application filed December 4, 1922. Serial No. 604,786.

To all whom it may concern:

Be it known that I, FREDRICK H. GRIFFITH, a citizen of the United States, residing at Johnstown, in the county of Cambria and State of Pennsylvania, have invented certain new and useful Improvements in Hair Crimpers and Curlers, of which the following is a specification.

The present invention relates to hair 10 crimpers and curlers an object of which is to provide a relatively small device which may be conveniently engaged with the hair and effectively secured thereto for maintaining the hair in a rolled up or convoluted position to thereby effect a curl in the hair which remains after the curling devices have been removed.

A co-ordinate object of the invention is to provide hair carried curling members which 20 are preferably made of a special metal to cause the hair to automatically adhere to said members, means also being provided to mechanically secure the hair to said members.

Other objects of the invention will be apparent from the following description of the present preferred form of the invention taken in connection with the accompanying drawings wherein:—

Fig. 1 is an elevational view of a hair curler constructed in accordance with this invention illustrating its application;

Fig. 2 is a perspective view of the hair curler per se;

Fig. 3 is a transverse sectional view of the curler illustrating its application; and

Fig. 4 is an elevational view of the curler showing the manner of engaging the hair beneath the resilient clamping member.

The device of this invention consists especially of a cylindrical body 5 which in the present instance is shown as equipped with a core 6 which has a pintle 7 extended from one end thereof offset from the longitudinal axis of the core. The opposite end of said core has a lug or ear 8 extended therefrom. Both the pintle 7 and lug 8 lie beyond the terminals of the body 5. By preference, the body 5 is composed of a highly conductive metal since it has been found by experiment that a highly conductive metal, such as copper, will cause automatic adherence of the

hair, to a limited extent, to the periphery of the body thereby facilitating engagement of the hair beneath mechanical clamping 55 means hereinafter described and furthermore effecting a more pronounced curl in the hair.

In order to start the hair on the body 5 a resilient clamping member 9 is provided which in the present instance consists of a flat spring one end of which is inserted through a complementary opening in the periphery of said body adjacent the lug 8. The spring is arranged to lie in parallelism 60 with the body 5 and has the free end thereof terminated short of the end of the body 5 from which the pintle 7 projects. As shown in Fig. 4 the hair is first engaged beneath the clamp 9 pursuant to which the body 5 is rotated so as to roll up or convolute the hair on the body as shown in Fig. 3. In order to retain the hair in a convoluted position on the body 5, a clasp 10 is provided which, in the present instance, consists of a rod, 65 one end of which is engaged with the lug 8 and the opposite end formed to provide a hook 11 which is engageable with the pintle 7. The rod 10 may likewise be made of a resilient metal so as to flex under pressure 70 and thereby automatically adjust itself to the amount of hair rolled up on the body 5.

The device above described will provide a convenient and effective means for curling the hair without causing undue inconvenience to the wearer thereof or without tearing the hair. It is to be understood, however, that various changes may be made in this invention such as to size, proportions of parts, materials, etc., within the scope of 80 the appended claim.

What is claimed is:—

A hair curler including a cylindrical body equipped with terminal projections one of which is coincident with the longitudinal 85 axis of the body and provided with an aperture and the other offset from said axis, and a wire strand one end of which is formed to provide an eye for engagement through the aperture of the first said projection and the 90 opposite end formed to provide a hook for engagement with the other projection.

In testimony whereof I affix my seal.

FREDRICK H. GRIFFITH.
